(57) **CLAIM**

I claim, the ornamental design for an infrared heating cooker, as shown and described.

DESCRIPTION

FIG. 1 is a top and front perspective view of an infrared heating cooker, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is an enlarged detail view of a portion taken from reference "8" on FIG. 2.

1 Claim, 8 Drawing Sheets
